UNITED STATES PATENT OFFICE

167,676

BUG DEFLECTOR

Albert Chicorel, Detroit, Mich.

Application September 19, 1951, Serial No. 16,685

Term of patent 14 years

(Cl. D14—6)

To all whom it may concern:

Be it known that I, Albert Chicorel, a citizen of the United States of America, residing at Detroit, in the county of Wayne and State of Michigan, have invented a new, original, and ornamental Design for a Bug Deflector, of which the following is a specification, reference being had to the drawing, forming a part thereof.

Fig. 1 is a front view of the bug deflector, embodying my new design.

Fig. 2 is a top view thereof.

Fig. 3 is a bottom view of the bug deflector.

Fig. 4 is a perspective view of the bug deflector.

Fig. 5 is an end view of the bug deflector.

Fig. 6 is a sectional view along the lines 4—4 in Fig. 1.

The dominant features of my bug deflector reside in those portions shown in solid lines.

I claim:

The ornamental design for a bug deflector, substantially as shown and described.

ALBERT CHICOREL.
